UNITED STATES PATENT OFFICE

ABE O. SAMUELS AND MAURICE L. WARNER, OF ROCHESTER, NEW YORK, ASSIGNEES
TO SAMSON-UNITED CORPORATION, OF ROCHESTER, NEW YORK, A CORPORATION OF
DELAWARE

SADIRON

Application filed May 21, 1930. Serial No. 454,269.

This invention relates to improvements in sad irons, and especially to sad irons of the kind which are heated electrically and generally employed for ironing or pressing clothes. Such irons are sometimes thermostatically controlled, that is, means are provided for breaking the electric circuit through the heating unit when a given maximum temperature is attained.

10 The principal object of this invention is to provide an iron of this kind which is simple in construction, inexpensive to make, which contains few parts and hence is less liable to get out of order, and in which the thermostatic control is more reliable than in irons heretofore constructed.

Another object of the invention is to construct an iron of this kind in which the thermostat element is adjacent the base of the iron, as near as possible to the working surface of the iron, the temperature of which is to be controlled thereby, thus securing more uniform control at the desired point.

A further object of the invention is to construct an iron of this kind in which the spring which cooperates with the thermostat element is adjustable toward and from the thermostatic element to vary the maximum temperature to which the iron may be heated, means being provided on the opposite side of the spring for adjusting it toward the thermostatic element, thus securing positive control and uniformity of operation.

To these and other ends the invention consists in the construction and arrangement of parts that will appear from the following description when read in conjunction with the accompanying drawings; the novel features being pointed out in the claims following the specification.

In the drawings:

Fig. 1 is a side elevation of an electric sad iron illustrating one embodiment of the invention, parts being broken away to expose underlying parts;

Fig. 2 is an enlarged fragmentary longitudinal section showing how the thermostatic element and its cooperating adjustable spring are mounted;

Fig. 3 is a fragmentary plan view of the

same on substantially the same scale as Fig. 1;

Fig. 4 is a sectional view taken substantially on line 4-4 of Fig. 2 and looking in the direction of the arrow at said line, and

Fig. 5 is a fragmentary sectional view taken substantially on line 5-5 of Fig. 1 and looking in the direction of the arrow at said line.

Referring more particularly to the drawings, in which similar reference numerals refer to the same parts in all the figures, the reference numeral 1 indicates the base or shoe of the sad iron which is or may be of any usual or preferred construction. Secured to the base by any suitable means, such as studs, is a clamp plate 2 which is made hollow or has a cut-out portion 3 on its underside to provide a housing for the working parts. The shoe and clamp plate may be constructed of cast iron, or other suitable material.

Arranged on the base or shoe within said housing is a heating element 4 which has an open center and rests in contact with the upper surface of the clamp plate, and is connected with a suitable source of electric current through the conductors 5 and 6 connected therewith by means of the binding posts 7 and 8. The conductor 5 is connected with one of a pair of connecting posts 9 mounted on a bracket 10 which has a forwardly extending portion 11 seated in a depression 12 in the upper surface of the clamp plate to which it is secured by means of a nut threaded on the upper end of a stud 13 threaded in a tapped opening in the shoe. The stud 13 passes through openings provided therefor in the clamp plate, and also serves to secure the rear end of the clamp plate and a hood and also the rear end of the handle 14 to the shoe or base. The front end of the handle 14, the clamp plate and the hood are secured to the base by means of a nut threaded on the upper end of a stud 15 similarly threaded in the base or shoe.

The conductor 6 extends forwardly from the post 8 and at its forward end is connected with an ear 16 projecting upwardly from the side of the rear end of the thermostatic element 17. The thermostatic element has an opening whereby it is arranged on a central projection 18 on a block 19, from whence it

extends forwardly and at its forward end has a contact point 20 arranged on its upper surface. The block 19 is of non-conducting material, and by this arrangement serves to support and insulate the thermostatic element spaced from but closely adjacent the upper surface of the shoe.

- The contact 20 cooperates with and is normally in contact with an opposing contact point 21 carried on the end of a spring 22. The spring 22 extends rearwardly from its contact point, and at its rear end has an opening whereby it is mounted on a block 23 supported on the block 19 and the thermostatic element. The block 23 is of non-conducting material and serves to separate or space the spring from the thermostatic element, and the blocks 19 and 23, and the thermostatic element 17 and spring finger 22 are secured to the shoe by means of a screw 24 which passes through a washer 25 on the spring 22, an enlarged opening in the spring 22, and openings in the blocks 23 and 19 and engages a tapped opening in the shoe. By this construction, the parts are secured to the shoe by a single securing means, the thermostatic element 17 being spaced and insulated from the shoe by the block 19, and at their rear ends the thermostatic element and the spring are spaced and insulated from each other by means of the block 23, the whole being housed in the clamp plate 2. The screw 24 and washer 25 are insulated from the finger 22 by an insulating element 25a.
- It is desirable to secure the thermostatic element and the spring 22 in longitudinal alignment with each other. To this end, the block 23 is provided with projections or flanges 27 and 28 between which the spring 22 is engaged. It also has a downward projection 29 which engages one side of the thermostatic element 17. By this arrangement, possible accidental disalignment of the parts is prevented since the flanges 27, 28 and 29 prevent relative rotation about the screw as a center, which screw provides a means for firmly clamping the parts to the shoe.
- The spring 22 has an upwardly projecting flange 31 at its rear end, whereby it is connected with one of the posts 9 by means of a conductor 32. Normally the parts are in the position shown in Fig. 1 of the drawings, in which the contacts 20 and 21 engage each other, and the circuit through the spring 22 and the thermostatic element 17 is closed, so that the current may flow through the heating element and heat the shoe. As the temperature of the shoe rises, the thermostatic element 17 becomes heated, the heat having a tendency to straighten it, due to uneven expansion of its parts, until a given maximum temperature is attained, when the thermostatic element straightens sufficiently to move its contact 20 from engagement with the contact 21 on the spring 22 to break the current

and prevent further heating of the shoe. As the shoe cools, the element again moves toward and into contact with the contact 21, and reestablishes the circuit through the heating unit. By this arrangement, a substantially uniform temperature may be secured in the shoe for a given class of work, and any danger of overheating the shoe is prevented.

In performing different classes of work with the iron, different temperatures are required for greatest efficiency, such as the nature of the goods, as cotton, silk or wool, also the moisture content, and it is therefore desirable that means be provided for varying the temperature at which the circuit is broken. To this end, the spring 22 and thermostatic element are provided with aligned openings intermediate their ends in which a screw 34 is arranged out of contact therewith and at its lower end engages a tapped opening in the shoe. Arranged on this screw and seated in the opening in the spring 22 is a block or ring 35 of non-conducting material, and the screw is enlarged or shouldered at 36 to engage this ring, or a washer 37 arranged between the shoulder and the ring. It will be noted that by this construction, the shoulder on the screw serves as a stop for the spring arm 22 and turning the screw in one direction threads it into the shoe and moves the shoulder or stop 36 against the ring 35 and moves it against the spring or resilient member 22 and flexes it to move its contact point 21 toward the contact point 20 so that greater heat action or a higher temperature is required to separate the contact points. When the screw is turned in the opposite direction, the contact point 21 moves in the opposite direction by virtue of the resiliency of the spring 22 and a lower maximum temperature of the shoe is required to separate the contact points.

Convenient means accessible from outside the hood are provided for turning the screw to vary the position of the contact point 21. To this end, the screw is knurled, corrugated or toothed at 39 above the shoulder 36 and projects through openings provided therefor in the hood and clamp plate 2. Arranged on the upper end of the screw is a finger piece 40 preferably constructed of non-conducting material and provided with a downwardly projecting internally corrugated or toothed sleeve 41 which engages the corrugations on the screw so that the screw may be turned thereby.

At its lower end, the sleeve 41 is threaded externally and has a nut 42 threaded thereon which has a recess in its upper face in which a collar 43 is seated, which has a laterally projecting annular flange 44 which rests on the upper side of the nut 42. The sleeve 41 is slotted at 45 for cooperation with a lug 46 on the flange 44, whereby the ring or collar 43 engages the sleeve 41 to rotate therewith. The flange 44 also has an outwardly project-

ing lug 47 which engages one side or the other of a fixed lug 48 depending from the hood or casing 49 arranged on the clamp plate. By this arrangement, rotation of the screw 34 is limited to less than a complete revolution, and only a limited range of adjustment of the contact 21 relatively to the contact 20 is provided. Means are provided for retaining the screw 34 in adjusted position. Said 10 means comprises a spring in the form of a split ring 51 which is arranged on the flange 44 and frictionally engages the inner wall of the hood 49.

By arranging the thermostatic element 17 adjacent the shoe and within the heating element, it receives the heat directly therefrom and is more sensitive to temperature changes therein than is the case when otherwise arranged. The adjustment of the spring 22 is 20 positive and provides a means for regulating the maximum temperature of the shoe and uniformly maintaining such temperature. An electric sad iron constructed as above is simple in construction, contains few parts, 25 and is adapted to maintain a uniform maximum temperature at all times.

Although only one embodiment of the invention is described herein, it will be understood that this application is intended to cover 30 such changes or modifications as come within the spirit of the invention or scope of the following claims.

We claim:

1. The combination of a support, a thermostatic element rigidly secured at one end to the support and having an opening intermediate its ends and arranged adjacent the support, an electric contact mounted on the other end of said thermostatic element, a resilient arm also rigidly secured at one end to the support and arranged above the thermostatic element and having an opening intermediate its ends in alignment with the opening in the thermostatic element, a second electric contact on the other end of said arm adapted to cooperate with the first mentioned contact, and means arranged in said aligned openings and engaging the support for flexing said arm to move its contact toward the first mentioned contact.

2. The combination of a support the temperature of which is to be controlled, a thermostatic element rigidly secured at one end to the support and having an opening intermediate its ends and arranged adjacent to the support, an electric contact mounted on the other end of said thermostatic element, a resilient arm also rigidly secured at one end to the support and arranged above the thermostatic element and having an opening intermediate its ends in alignment with the opening in the thermostatic element, a second electric contact on the other end of said arm adapted to cooperate with the first mentioned contact, adjustable means arranged

in said aligned openings and engaging the support, and a stop on said adjustable means operatively engaging the upper face of said arm for limiting its movement away from the thermostatic element.

3. The combination of a support, a thermostatic element rigidly secured at one end to the support and arranged adjacent thereto, an electric contact mounted on the other end of said thermostatic element, a resilient arm also rigidly secured at one end to the support and having an opening intermediate its ends, the thermostatic element being located between the support and the resilient arm, a second electric contact on the other end of said resilient arm adapted to cooperate with the first mentioned contact, and means extending through said opening in the resilient arm and adjustably engaging the support for flexing said arm to move its contact toward the first mentioned contact.

In witness whereof, we have hereunto signed our names.
